UNITED STATES PATENT OFFICE.

HARRY A. DAVIS, OF HOPEDALE, MASSACHUSETTS, ASSIGNOR TO DRAPER CORPORATION, OF HOPEDALE, MASSACHUSETTS, A CORPORATION OF MAINE.

TENSION DEVICE FOR YARN-WINDING MACHINES.

Application filed April 19, 1926. Serial No. 102,875.

This invention relates to means for controlling the tension on the yarn as it is drawn off from a yarn carrier upon which the yarn is wound with a weft wind and wound on to a receiver. More particularly the invention relates to thus controlling the tension on the yarn in a spooler where the yarn is wound off from a weft wound filling carrier or bobbin on to a spool.

In such machines it is very important that the yarn shall be wound on to the receiver or spool under as uniform tension as possible and free from kinks. If the yarn balloons as it is drawn off from the yarn carrier and if the tension on the yarn is irregular, kinks in the yarn are very apt to form and be retained in the yarn as it is wound on the receiver or spool. Such a kink then passes into the warp or filling and affects the weaving operation, such as producing an imperfection in the cloth or causing the operation of the warp stop motion.

The yarn carrier is mounted in a suitable standard secured on the frame of the machine with a yarn guide on the standard beyond and in line with the axis of the yarn carrier to direct the yarn to the traverse rod which moves vertically to traverse the yarn over the receiver or spool. The run of yarn from the yarn carrier to this yarn guide and the run of yarn from the yarn guide to the receiver or spool must both be under control so that the tension of the yarn in each of these runs shall be even and ballooning of the yarn prevented with its consequent formation of kinks.

The object of the invention is to control the tension on the yarn in both of these runs and thus secure a satisfactory wind on the receiver or spool.

The object of the invention is further to provide a tension mechanism in which one or more cords extend longitudinally of the yarn carrier in contact with the yarn mass and in which these cords are under tension which maintains them in contact with the yarn mass and thus prevents ballooning and secures the requisite tension in the yarn as it is drawn off from the yarn carrier and passes to the yarn guide.

The object of the invention is further to secure the required tension in the aforesaid cord or cords by means of the longitudinal elasticity of the cord or cords.

The object of the invention is further to provide supporting means for the cord or cords employed in the preferred form of the invention by means of which a ready doffing of the yarn carrier from its support may be secured.

These and other objects and features of the invention will appear more fully in the accompanying description and drawings and will be particularly defined in the claims.

The drawings illustrate so much of an ordinary spooler as is necessary to disclose a preferred application and embodiment of the present invention.

As the general construction and operation of a winding machine and in particular of a spooler is well known and familiar to those skilled in the art and as the construction of the invention employed is repeated in each winding unit of the machine, it is unnecessary here to illustrate and describe anything more than those features directly concerned with the present invention and also but a single unit of the machine.

In the drawings:

Fig. 1 is a view in side elevation and partially in vertical cross section of a portion of a spooler with the preferred form of the invention embodied therein.

Fig. 2 is a side elevation of a tension device applied to the traverse rod.

Fig. 3 is a front elevation of the construction shown in Fig. 2.

Fig. 4 is a front elevation of the standard and construction embodied therein shown in Fig. 1.

Fig. 5 is a view similar to the lower portion of Fig. 4 illustrating a modification.

Fig. 6 is a rear elevation of the yarn guide and tension mechanism looking toward the left in line with the axis of Fig. 7.

Fig. 7 is a top plan view normal to the axis of the standard and mechanism connected therewith shown in Fig. 1.

Fig. 8 is a front elevation with the yarn guide and parts supported thereby shown in Figs. 1, 4 and 7 removed and looking toward the right of Fig. 7 in line with the axis.

Fig. 9 is a view similar to Fig. 8 with the yarn carrier removed and with the arm swung to doffing position.

A portion of the frame 1 of a spooler is shown with the transverse beam 2 on which is mounted the spindles for the yarn re-

ceivers or spools 3. Each spool is driven in the usual manner by a whirl 4. The traverse rod 5 is reciprocated up and down by the usual mechanism to traverse the yarn longitudinally of the spool as it is wound thereon. A rod 6 extends transversely of the frame and to this rod is secured separate standards, one for each spool.

In the present construction, the standard 7 10 extends forwardly and upwardly and is secured to the rod 6 by a bifurcated portion locked to the rod by a set screw 8. At its lower end the standard 7 is provided with a laterally projecting base 9 on which is mounted a suitable support herein shown as a stud 10 for the yarn carrier or bobbin 11. The yarn is wound on this carrier with the usual weft or filling wind so that it is unwound or drawn off from the yarn carrier 20 by pulling it longitudinally off the tip 12. With this type of wind the yarn is laid in conical layers on the carrier and consequently, if unrestrained, unwinds at a varying speed and with varying tension.

25 A yarn guide is mounted on the standard beyond and in line with the tip of the yarn carrier. In the construction illustrated, this yarn guide is shown as a forked projection 13 extending laterally of the standard 7 in 30 which is mounted at the base of the forked portion a vitreous roll or stud 14 over which the yarn is guided. Preferably also a second vitreous roll or stud 15 is mounted in the yarn guide and beyond the roller stud 14 to direct the yarn back toward the traverse rod.

40 A shaft or rod 16 is journalled at its lower end in the base of the standard 7 and at its upper end in a lateral projection 17 on the standard. This projection at its upper face is provided with a lug 18 having a shoulder 19. The base 20 of the yarn guide is rigidly secured to the end of the rod 16 and is provided on its lower face with a lug 21 having a shoulder 22 cooperating with the shoulder 19. When the shoulders 19 and 22 are in contact, the yarn guide is in its normal position. The yarn guide may, however, be 45 swung to the right, viewing Fig. 4, turning with the rod 16 and be thus carried out of line with the axis of the yarn carrier to permit the doffing of the yarn carrier from its support.

An arm 23 is secured to the rod 16 and 55 is adjustable rotarily and longitudinally thereof by means of the set screw 24 in the hub 25 of the arm mounted on the rod. This arm 23 is curved to extend well around and circumferentially of and beyond the yarn carrier at a position above or beyond the tip of the yarn carrier and consequently between this tip and the yarn guide 13.

The required tension on the yarn mass 26 60 of the yarn carrier is secured in this invention by one or more cords. In a simple and

preferred arrangement illustrated, two such cords are employed, but the number may be varied as required. In the construction illustrated, one cord 27 extends from a point 28 in the base 9 up to a point 29 on the projection 17. This cord extends longitudinally of the yarn carrier and preferably helically and the direction of its path may be adjusted, in the construction shown, by securing the upper end in one of the several 70 holes 29. The second cord 30 illustrated is preferably mounted at a point 31 in the base substantially diametrically opposite to the point 28 and extends longitudinally of the 75 yarn carrier and is mounted at the upper 80 end 32 in the end of the arm 23. This cord also therefore preferably extends helically of the yarn carrier and in a direction opposite to that of the cord 27.

Suitable means are provided for producing tension in the cord or cords employed so as to maintain them when in operative position in contact with the yarn mass. This tension is preferably produced as in the construction shown in Figs. 1, 4, 7, 8 and 9 90 by making the cords themselves longitudinally elastic and mounting them so that they are held taut and snug against the yarn mass throughout the unwinding operation. But other means may be employed. For 95 example, as shown in Fig. 5, the cords are shown of a non-elastic character extending through holes in the base 9 and provided at their lower ends with weights 33. These 100 weights, the size and amount of which may be varied as desired, act to produce the required tension in the cords.

When it is desired to doff the yarn carrier, and by that phrase is meant either placing a fresh yarn carrier on the said support or removing the unwound yarn carrier therefrom, the yarn guide 13 is swung to the right, viewing Fig. 4, thus rotating the rod 16 and swinging with it the arm 23. This carries the upper end of the cord 30 110 circumferentially or away from the yarn carrier and unwinds the cord 30 and lifts it away from the yarn mass. Usually also, where two cords are employed, the other cord 27 is held up against the yarn mass by engagement with the arm 23 and by the cord 30 overlapping the cord 27, so that when the shaft 16 is thus rotated, this cord 27 is relieved so as to move away somewhat from the yarn mass. Thus, the yarn guide and 115 the arm 23 being out of the way and the cords freed, the yarn carrier may be readily removed from or placed on the supporting stud.

This tension mechanism is found very 120 effective in equalizing the tension on the 125 yarn as it is drawn off the yarn carrier over the yarn guide, the cord or cords lying in contact with the yarn mass and giving a yielding frictional action on the yarn which 130

produces the required tension. The adjustments provided at the upper ends of the cords and the ability to vary the yield or stretch of the cords, when of the elastic character, or to vary the weights when of the non-elastic character, enable the tension to be controlled very accurately. As a result, there is practically no ballooning of the yarn on the run from the yarn carrier to the 10 yarn guide and no kinks are formed.

A suitable tension device is located between the yarn guide and the receiver or spool upon which the yarn is wound so as to control the tension on the yarn in this 15 run. This tension device may be mounted either from the standard or from the traverse rod and a suitable device is shown for both positions.

In Figs. 1, 4, and 7 the tension device is 20 shown as mounted from the standard and conveniently on the yarn guide. In the construction illustrated, a metal box-like structure 34 open at the top and bottom is supported directly over the guiding stud or 25 roll 14. This box is supported by a depending portion 35 of one side wall connected by screws 36 to the yarn guide and conveniently serving to hold in place the roll or stud 14. Cylindrical rolls of adjustable weight are 30 guided in the box and rest upon the yarn as it passes over the roll or stud 14. As shown, these cylindrical weights 37 are concentric metal cylinders so that one may be employed or a plurality nested to give the required 35 pressure and consequent tension on the yarn. A projection 38 extends laterally from the yarn guide and serves as a threading guide to direct the yarn beneath the rolls 37 in threading up the machine.

40 A similar tension device is shown in Figs. 2 and 3 for mounting on the traverse rod 5. In this case the box 39 is supported from a bracket 40 bolted to the bracket 41 carrying the usual clearer 42, the two brackets clamping the traverse rod 5. A pointed polished steel or vitreous cylindrical stud 43 projects laterally from the bracket 40 directly beneath the box 39 and the weighted rolls 37 rest on the yarn as it passes over this stud. 45

50 A laterally projecting guide arm 44 serves to direct the yarn in threading between the roll 37 and the stud 42.

Thus by the use of either of these tension devices the tension on the run of yarn extending from the yarn guide 13 to the yarn receiver or spool is efficiently controlled.

There is thus presented a simple, effective and efficient means for controlling the tension on the yarn as it passes from the yarn 60 carrier to the yarn receiver and one which may be readily attached to existing spoolers. The mechanism is particularly useful in connection with hard twisted yarn which under ordinary conditions is very likely to kink, 65 but it is applicable for all purposes.

Having thus described the invention, what is claimed as new, and desired to be secured by Letters Patent, is:

1. A tension mechanism for yarn winding machines comprising a standard, a support 70 on the standard for a weft wound yarn carrier, an arm mounted on the standard to swing transversely of the tip of the yarn carrier, a cord extending from the base of the standard helically of the yarn carrier 75 to a point on the standard beyond the tip of the yarn carrier, a second cord extending from another point on the base in the opposite direction helically of the yarn carrier to a point on the arm, means for producing 80 tension in said cords to maintain them in contact with the yarn mass, whereby the yarn is maintained under the required tension and prevented from ballooning as it is drawn off the yarn carrier in the winding 85 operation and whereby, when the arm is swung aside, the second cord is unwound to permit the ready doffing of the yarn carrier.

2. A tension mechanism for yarn winding machines comprising a standard, a support 90 on the standard for a weft wound yarn carrier, an arm mounted on the standard to swing transversely of the tip of the yarn carrier, a pair of cords extending from substantially diametrically opposite points of 95 the base, the one to a point on the standard beyond the tip of the yarn carrier and the other to a point on the arm, means for producing tension in said cords to maintain them in contact with the yarn mass, whereby 100 the yarn is maintained under the required tension and prevented from ballooning as it is drawn off the yarn carrier in the winding operation and whereby, when the arm is swung aside, the second cord is unwound 105 to permit the ready doffing of the yarn carrier.

3. A tension mechanism for yarn winding machines comprising the construction defined in claim 1, together with means for 110 adjusting the said arm rotarily of its axis thereby to vary the position of the end of the cord connected to the arm circumferentially of the yarn carrier.

4. A tension mechanism for yarn winding 115 machines comprising a standard, a support on the standard for a weft wound yarn carrier, a cord mounted in the standard and extending longitudinally of the yarn carrier, means for producing tension in said 120 cord to maintain it in contact with the yarn mass, and means for adjusting the point at which one end of the said cord is mounted in the standard circumferentially of the 125 yarn carrier thereby to vary its line of contact with the yarn mass, whereby the yarn is maintained under the required tension and prevented from ballooning as it is drawn off the yarn carrier in the winding 130 operation.

5. A tension mechanism for yarn winding machines comprising a standard, a support on the standard for a weft wound yarn carrier, a plurality of cords mounted in the standard and extending in different paths longitudinally of the yarn carrier, means for producing tension in said cords to maintain them in contact with the yarn mass, and means for adjusting the points at which
- 5 10 one end of each of the said cords is mounted

in the standard circumferentially of the yarn carrier thereby to vary the lines of contact of said cords with the yarn mass, whereby the yarn is maintained under the required tension and prevented from ballooning as it is drawn off the yarn carrier in the winding operation.

In testimony whereof, I have signed my name to this specification.

HARRY A. DAVIS.
